UNITED STATES PATENT OFFICE

92,847

DESIGN FOR A DESK OR SIMILAR ARTICLE

James R. Jones, Jamestown, N. Y., assignor to
Art Metal Construction Company, Jamestown,
N. Y.

Application May 9, 1934, Serial No. 51,728

Term of patent 7 years

To all whom it may concern:

Be it known that I, JAMES R. JONES, a citizen of the United States, residing at Jamestown, Chautauqua County, State of New York, have invented a new, original, and ornamental Design for a Desk or Similar Article, of which the following is a specification, reference being had to the accompanying drawing, forming a part thereof.

In said drawing:

Fig. 1 is a front perspective view of a desk or similar article embodying my invention.

Fig. 2 is a rear perspective view thereof.

According to my design the front and rear edges of the flat top of the desk are rounded off and substantially flush with the front and rear upright faces of the body, and rounded finishing bands form the end edges of the top, which are substantially flush with the upright end faces of the body, and the legs of the desk are set back or inwardly from the sides and ends of the body.

I claim:

The ornamental design for a desk or similar article, substantially as shown and described.

JAMES R. JONES.
